FLASH CARD GAME DEVICE

Ruth S. Chuy and Daniel T. Chuy, both of 15447 Sorrento,
Detroit, Mich. 48227

Filed Sept. 12, 1966, Ser. No. 3,812

Term of patent 14 years

(Cl. D25—1)

fig. 3.

FIG. 1 is a front elevational view of a flash card game device illustrating our new design;

FIG. 2 is a left side view thereof;

FIG. 3 is a top view thereof;

FIG. 4 is a right side view thereof; and

FIG. 5 is a rear elevational view thereof.

The broken line showing of flash cards is for illustrative purposes only.

We claim:

The ornamental design for a flash card game device, substantially as shown and described.
